US00D902210S

(12) **United States Design Patent** (10) Patent No.: **US D902,210 S**
Jensen et al. (45) Date of Patent: **** Nov. 17, 2020**

(54) **ELECTRONIC BASE STATION**

(71) Applicant: **JACOB JENSEN DESIGN A/S**,
Hoejslev (DK)

(72) Inventors: **Timothy Jacob Jensen**, Hoejslev (DK);
Danny Li, Shanghai (CN); **Marina**
Lothigius, Shanghai (CN)

(73) Assignee: **JACOB JENSEN DESIGN A/S** (DK)

(**) Term: **15 Years**

(21) Appl. No.: **29/650,955**

(22) Filed: **Jun. 11, 2018**

(51) LOC (12) Cl. **14-99**

(52) U.S. Cl.

USPC **D14/433**; D14/240; D14/358

(57) **CLAIM**

The ornamental design for an electronic base station, as shown and described.

DESCRIPTION

FIG. 1 is a front elevation view of a first embodiment of an electronic base station showing our new design;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top and front perspective view thereof;

FIG. 8 is a top and back perspective view thereof; and,

FIG. 9 is a bottom and front perspective view thereof.

1 Claim, 9 Drawing Sheets
